[57] ABSTRACT

A method of constructing multi-story buildings by the Lift-slab Method in which the floor slabs, bearing walls and partition walls if desirable are pre-cast on the ground level, in a horizontal stacked relationship, substantially in vertical alignment with their ultimate positioning in the completed structure; temporary removable columns are fixed in place, relative to said stacked floor slabs and bearing walls, which are provided with appropriate lifting means mounted on top thereof whereby each floor slab is lifted and positioned at its respective level and the bearing walls are pivoted from their horizontal positions to their permanent respective fixed vertical positions, the temporary columns thereafter are removed and the bearing walls provide the entire support for the structure.

**METHOD FOR MANUFACTURING MULTI-STORY
 HOUSING WITH FLOOR-SLABS, BEARING
 WALLS AND PARTITIONS CAST ON THE
 GROUND LEVEL**

STATE OF THE PRIOR ART

In the erection of multi-story buildings, by using the generally conventional form of the Lift-Slab Method, permanent columns are erected for subsequent use in lifting the various floor slabs to their respective levels whereupon the slabs are permanently anchored to said columns, the columns thereby becoming the permanent bearing elements for the building. The walls, generally applied to buildings, comprising this type of basic construction, are made light and thin as they perform no bearing function, however, light, thin walls, while they save on construction material and resulting weight, provide very poor insulation against sound. As it is not economically justifiable to increase the thickness of the walls, and the resulting weight thereof, to a degree necessary to provide for good sound insulation, the area of use of the Lift-Slab Method has been quite limited.

Buildings, for instance, multi-story apartment buildings, where a good sound insulation is necessary between apartments, are therefore built by conventional methods, with thick, heavy walls which provide good sound insulation as well as serving as support for the floor-slabs.

In this type of construction, if the Lift-Slab Method were employed, the building would receive two expensive bearing systems which is not economically practical.

BRIEF DESCRIPTION OF THE INVENTION

The present invention relates to a method by which buildings, such as multi-story apartment buildings, may be constructed utilizing the Lift-Slab Method while providing heavy bearing walls. Removable lifting columns are employed to accomplish the positioning of the various floor slabs, along with their associated bearing walls, at their respective floor levels and for holding the floor slabs in their respective positions while the bearing walls are erected and permanently anchored in place. The floor slabs and bearing walls are all formed and cast of concrete in a stacked relation in a position to be directly, vertically elevated to their respective positions of temporary attachment to the columns. After all of the floor slabs and their respective bearing walls, in their fixed vertical positions, have been subsequently moved to their final fixed levels in the building, the lifting columns are removed leaving the bearing walls as the sole support of the building.

BRIEF DESCRIPTION OF THE DRAWINGS

FIG. 1 is a schematic top plan view of a stack of cast floor slabs and bearing walls, and the temporary lifting columns which are used to lift the floor slabs and bearing walls to their respective floor levels;

FIG. 2 is a fragmentary longitudinal sectional view taken on line 2-2 of FIG. 1;

FIG. 3 is a schematic side elevational view of a typical building being constructed according to the method of the present invention;

FIG. 4 is a schematic side elevational view similar to FIG. 3 illustrating all of the floor slabs and bearing

walls, in the main section of the building, fully erected;

FIG. 5 is a vertical sectional view schematically illustrating one type of hinged connection between the top edge of the bearing wall and the immediate on top floor slab;

FIG. 6 is a vertical sectional view schematically illustrating a lock and lowering mechanism for a bearing wall pivotally attached to the underneath side of a floor slab as in FIG. 5;

10 FIG. 7 is a vertical sectional view schematically illustrating a hinged connection between the lower edge of a bearing wall and the immediate underneath floor slab;

15 FIG. 8 is a top plan view of a lifting mechanism by which a bearing wall is automatically pivoted upwardly from a horizontal position to an approximate vertical position when the immediate on top floor slab is lifted; and

20 FIG. 9 is a longitudinal sectional view taken along the line 9-9 of FIG. 8 illustrating the lifting mechanism.

**DETAILED DESCRIPTION OF THE METHOD OF
 THE PRESENT INVENTION**

With reference to the drawings and particularly to 25 FIGS. 1 and 2, the removable columns 10 are illustrated installed and positioned relative to the shape and size of the multi-story building to be constructed and the appropriate floor slabs indicated generally at 12 and bearing walls 14 are pre-cast in a stacked relation 30 on the ground level generally within the confines of the temporary lifting columns whereby they may be subsequently lifted vertically to their respective predetermined positions.

As best illustrated in FIG. 2, the bottom floor slab 16 35 is formed and cast of concrete on the ground level and said floor slab 16 functions as the bottom form for the first layer of bearing walls 18 which are properly edge formed to the desired dimensions. After the first layer of bearing walls is cast, subsequent layers of alternating floor slab and bearing walls are pre-cast in a stacked horizontal relation. All voids such as 20 and 22 are enclosed by appropriate forms which, along with other appropriate edge forms, are provided as the pre-casting of alternating levels of floor slabs and bearing walls progresses upwardly until the desired number of floor slabs and associated bearing walls is completed as determined by the number of floor levels in the building under construction.

50 An appropriate release compound 23 is provided between each of the above-described alternating layers of floor slabs and bearing walls as well as around the surfaces of the temporary columns 10 which come in contact with the concrete. It may be desirable to form the floor slabs slightly away from the columns 10.

55 Beams 24, if desirable, may be fixed in spanning relation to the tops of the columns 10 as illustrated in FIG. 2 to support a temporary roof enclosure 25.

Referring to FIG. 3, conventional lifting means 26 60 such as jacks are schematically illustrated fixed to the upper distal ends of each lifting column 10 and the columns 10 are preferably hollow with vertical side slots 28 and 30 as illustrated in FIG. 8 whereby any type of conventional lifting rods, cables or the like may be extended vertically downwardly from the lifting means 26 through the columns 10 for attachment to the floor slabs or bearing walls through slots 28 and 30 to provide for vertical movement thereof.

With further reference to FIG. 3, lifting beams 32 are illustrated schematically attached to the upper two floor slabs 34 and 36 which have been lifted by the lifting means 26 to the top of the columns 10 where they are temporarily anchored to said columns 10. In like manner the floor slabs 38 and 40 have been lifted and similarly anchored to the columns 10 at a point intermediate the height of the building. The associated bearing walls 35, 39, 41 etc. as illustrated remain in horizontal positions, either sandwiched inbetween or on top of the floor slabs 34, 36, 38 and 40.

The lower floor slabs 42, 44 and 46 are illustrated in FIG. 3 at their predetermined levels with their associated bearing walls fixed in their respective vertical load bearing positions. The next operation as viewed in FIG. 3 will be to attach the various horizontally disposed bearing walls 41 to the floor slab 38 in a manner by which said walls 41 will automatically be erected to their approximate vertical positions when the floor slab 38 is lifted a suitable distance. The ends 50 of the bearing walls 41 are pivotally attached to the floor slab 40 and when the floor slab 38 is lifted, the bearing walls 41 are pivoted upwardly on the floor slab 40. In this general manner the bearing walls 41 are vertically positioned between the floor slabs 38 and 40 as seen in FIG. 4.

Next, the lifting beams 32 are removed from the floor slab 38 and floor slab 36 is lowered into contact with the bearing walls 39 and attached thereto in a manner whereby the walls 39 are automatically pivoted upwardly when slab 36 is lifted. The walls 39 assume their vertical positions as seen in FIG. 4 in the same manner as described relative to walls 41. In the final step the walls 35 which are pivotally attached to the underside of slab 34 are pivoted downwardly as shown in FIG. 4.

The lifting beams are utilized to distribute the lifting forces on the concrete slabs in approximately the same manner as the reactions from the slabs on the bearing walls in the finished building, thus the floor slabs are designed only for the loads imposed thereon by the finished building without additional reinforcing for lifting purposes.

With reference to FIG. 7, the bearing wall 14 is illustrated hinged to a floor slab 12 by hinge means 60 including one end portion 62 embedded in the wall 14 and a second end portion 64 embedded in the slab 12 whereby the wall 14 may be pivoted from its horizontal position illustrated in dot-dash lines 14' to the vertical position illustrated in full lines. Rigid connecting means may be provided between the lower end of the wall 14 and the slab 12 by welding, as illustrated at 64, a U-shaped channel 66, cast on the lower end of said wall, to members such as the angle irons 68 cast in the floor slab. A mortar bed 70 may also be provided to seat the wall 14 on the slab 12. The hinges 60, channels 64 and angle irons 68 are all placed in the initial casting of the walls 14 and slabs 12.

After the bearing walls 14 have been fixed in their vertical positions as described, the lifting rods or cables may be fixed to the walls for elevating one complete floor slab and associated bearing wall assembly to its predetermined elevation. The hinge means 60 preferably extends across the width of the lower end of the bearing walls 14 to distribute the lifting forces in the same manner as provided by the lifting beams 32.

FIG. 5 illustrates a hinged connection 74 between a slab 12 such as the roof slab 34 in FIG. 4 and bearing

walls 35 where it is desirable to have the bearing walls pivot downwardly to vertical positions as indicated by arrows 78, from a horizontal position 35' underneath the slab 34. The hinge 74 includes an end portion 80 embedded in the slab 34 and end portions 82 and 84 embedded in the wall 35. A mortar bed 85 may also be used to seal the connection. If desirable a welded connection may be provided in the same manner as illustrated for the bottom connection in FIG. 7.

FIG. 6 illustrates schematically one means of providing a lock and lowering arrangement 86 whereby a wall is maintained in a horizontal position beneath a concrete slab 12 such as occurs in FIG. 3 after the floor slab 36 is lowered. A cable or rod 87 is embedded in the wall 14 adjacent its future lower end and extends upwardly through a clearance hole 88 in the slab 12. Lock means 89 is fixed to the cable 87 against the upper face of the slab 12, the removal of which permits the wall to swing downwardly about a pivot as illustrated in FIG. 5. Controlled swinging movement may be provided by attaching a winch or other type of control means to the cable or rod 87.

FIGS. 8 and 9 illustrate one method by which the bearing walls 14, which are normally horizontally disposed as at 14' between a pair of floor slabs 12, may be automatically erected to substantially vertical positions when the upper floor slab 12a is elevated. Slots 90 are provided in the floor slabs 12a which are substantially equal in length to the raised height of the walls 14 and rails 92 and 94 are disposed in opposed, parallel relation along both upper edges of each slot 90. Trolley devices 96 are operably disposed on the rails, each one of which provides a link 98 having a hooked lower end 100 depending downwardly between the rails and through the slot 90 for attachment, as at 102 to the upper end of a wall 14.

As illustrated in FIG. 9, when the upper floor slab, illustrated in dot-dash lines at 12' is disposed on top of the horizontal wall section 14', the hooked lower end 100 of the trolley link 98 is attached to the future upper end of the wall 14' as at 102'. It is to be noted that the rails 92 and 94 are downwardly inclined so that when the floor slab is raised from the position illustrated at 12' to the upper full line position 12a, the trolley 96 will automatically travel down the inclined rails and pivot the wall 14 about its lower hinged end to a substantially vertical position as indicated by the arrow 104.

In smaller buildings according to the method of the instant invention, the top slab 12 is lifted to the top of the columns 10 and temporarily anchored in place and the bearing walls 14 of the next floor slab 12 to be lifted are pivoted upwardly to their vertical positions and fixed in place as described relative to FIG. 7. The erected bearing walls are connected to the lifting rods or cables and the floor slab and bearing wall assembly is lifted to its predetermined level and anchored temporarily to the columns 10. The procedure is repeated until all concrete slabs and their associated erected walls are parked slightly above their approximate final elevation in the building. In the final step, the floor slabs are successively disconnected from the columns, beginning with the lowermost slab, and lowered slightly to their final fixed positions until all levels of floor slabs and connecting bearing walls are in place.

In tall buildings, such as illustrated in FIGS. 3 and 4, as previously described, the floor slabs and walls are

lifted in stages whereby the floor slabs are parked and temporarily spliced to the columns at various elevations, beginning at the top of the lifting columns. After the first floor bearing walls are erected, the floor slabs and bearing walls of each floor level, progressing upwardly, are lowered into place and the bearing walls erected as by the arrangement described relative to FIGS. 8 and 9 for example.

As further illustrated in FIGS. 3 and 4, long buildings are divided into sections of suitable length and interconnected by prefabricated elements 120.

It should also be noted that the walls 14, which have been identified generally as bearing walls, in some cases, depending on the structural strength requirements of each individual building, may include non-bearing partition walls.

While the preferred forms of the method of the present invention have been herein illustrated and described, various modifications and changes may be made, within the scope of the appended claims, without departing from the spirit of the invention.

What I claim is:

1. In the method of erecting and constructing multi-story buildings, at the construction site, whereby the ceiling and flooring elements are supported on vertically-disposed bearing walls and in which the elements may be manufactured in horizontal relation by casting on site, and in which the elements are erected to their installed positions by pivoting the bearing walls to a vertical position between the floor and ceiling ele- 30

ments, characterized by the steps of:

- A. temporarily installing a plurality of removable columns in geometric arrangement relative to the size and shape of the building being erected;
- B. pivotally connecting adjacent edges of certain of the bearing elements and floor and ceiling elements;
- C. elevating certain of the bearing elements and floor and ceiling elements, as a sandwiched unit, relative to the temporary columns and temporarily retaining them thereat whereby the elements have sufficient strength in their sandwiched relationship to resist strains placed thereon;
- D. pivoting the bearing elements into vertical load-bearing relation relative to the floor and ceiling elements;
- E. lowering the floor and ceiling elements into simple beam-supported relationship relative to said bearing elements; and
- D. removing the temporary columns whereby the primary bearing load support, ceiling and floor skeleton of the building is assembled without using columns and the like in the multi-story building.

2. The method as set forth in claim 1 further characterized by the step of pre-assembling the elements in such a pivoted relation and automatically erecting the bearing elements as the floor and ceiling elements are raised.
